UNITED STATES PATENT OFFICE.

HENRY BROWNLÉE, OF PORT HOPE, ONTARIO, CANADA.

ESCAPE DEVICE FOR SUBMARINES.

Application filed January 13, 1928. Serial No. 247,703.

My invention relates to improvements in escape devices for submarines, and the object of the invention is to devise simple means whereby the crew of a sunken submarine may 5 be easily rescued therefrom and thereby obviate the loss of life which has usually been incident thereto, and at the same time removing vitiated air and supplying fresh air to the interior of the submarine, and it consists 10 essentially of the arrangement and construction of parts as hereinafter more particularly explained.

Fig. 1 is a sectional view through a fragmentary portion of a body of a submarine 15 and my device applied thereto.

Fig. 2 is a plan sectional view on line 2—2 Figure 1.

Fig. 3 is a plan sectional view on line 3—3 Figure 1.

In the drawing like characters of reference 20 indicate corresponding parts in each figure.

1 indicates the shell of a submarine provided with an orifice 2. 3 is a cylindrical entrance chamber open at its upper end and 25 provided with a flange 3^x or any other suitable means for attachment to the shell 1 so as to depend therefrom into the interior of the submarine. The opposite end of the cylindrical chamber 3 is provided with a closure 4.

30 8 is an orifice formed in the periphery of the cylinder 3 provided with a door or other suitable closure 9. 10 is a cylindrical member forming an extension of the member 3 and provided with a flanged lower end 10^x by 35 which it is secured to the shell 1 by the same bolt securing the flange 3^x and in such a manner as to form a water tight joint. The upper end of the member 10 is also flanged at 10°.

40 11 is a cylindrical valve chamber provided 40 with flanged upper and lower ends 11^x and 11°, the flange 11° being secured to the flange 10° of the member 10. The valve chamber 11 is provided with a laterally extending arm 12 formed integral therewith and provided with 45 a flanged outer end 12^x.

45 13 is an extension to the portion 12 provided with a flanged inner end 13^x secured to the flange 12^x. The outer end of the portion 13 is closed, such closed end being provided 50 with a central orifice 13°. 14 is a packing gland secured to the closed end of the portion 13. 15 is a valve shaft which is rotatably mounted in the orifice 13 and held from longitudinal movement. The valve shaft 15 is 55 threaded. 16 is a slide valve or cut-off fitting guides formed in the sides of the valve cham-

ber 11 and provided with an internally threaded orifice 16^x into which the threaded shaft 15 extends.

By rotating the shaft 15 the valve 16 is 60 withdrawn into the lateral extensions 12 and 13 so as to open communication between the valve chamber 11 and the chambers 10 and 3. The valve shaft 15 is operated by the following 65 device.

17 is a standard secured to the floor of a submarine and in which is journalled the lower end of a vertical shaft 18. 19 is a bearing sleeve secured to the exterior face of the shell of the submarine and in which the upper 70 end of the shaft 18 is journalled. 20 are packing glands for forming a water tight joint between the upper end of the shaft 18 and the shell 1 of the submarine. 21 is a bevelled gear secured to the shaft 18 in proximity to the 75 standard 17 and 22 is a bevelled gear secured to the upper end of the shaft 19 projecting outwardly from the bearing sleeve 19. 23 is an arm extending from the standard 17 and provided with a horizontal bearing sleeve 24 80 in which is journalled a short shaft 25 to one end of which a bevelled gear 26 is secured. The bevelled gear 26 meshes with the bevelled gear 21.

27 is a control wheel secured to the opposite 85 end of the shaft 25. 28 is a bevelled gear secured to the outer end of the threaded shaft 15 and meshing with the bevelled gear 22.

It will thus be seen that one of the crew by 90 turning the control wheel 27 may withdraw the valve 16 whenever desired.

29 is a casting provided with a flanged lower end 30 secured by bolts 31 to the flange 11^x of the valve chamber 11. The casting 29 is provided at its lower end with an interior 95 flange 32 which may be bevelled as indicated.

33 are double lugs extending radially from the casting 29 and between which are pivoted eye-bolts 34. 35 is a diving bell which is carried and lowered from a relief ship and which 100 fits within the casting 29, a slight clearance being formed therebetween. 36 are double lugs extending from the diving bell in alignment with the lugs 33 and into engagement with which the eye-bolts 34 are swung being 105 secured in position by nuts 37 so as to draw the lower end of the diving bell 35 into tight engagement with the flange 32, a suitable packing being interposed between the abutting faces. 38 is a glass window formed in the 110 upper portion of the bell. 39 is a handle which the occupant of the bell may grasp. 40 are

cross bars upon which the feet of the occupant may rest. 41 is a pipe for supplying fresh air to the interior of the bell 35 and 42 is a pipe for withdrawing vitiated air from the bell. 5 43 is a pipe by which any water in the interior of the valve chamber may be drained into a suitable receptacle, the cessation of the flow of water acting as a signal to the operators to know that the bell is clear of water and ready 10 for release.

Having described the principal parts involved in my invention I will briefly describe the operation of the same.

When a submarine has been sunk divers 15 place a diving bell 35 in position securing it within the casting 29 by the bolts 34. The interior of the bell is then drained of water through the pipe 43 and one of the crew then enters the chamber 3 by means of the door 9, 20 such door then being closed. The valve 16 is then withdrawn by turning the hand wheel 27. The occupant of the chamber 3 then climbs through the open valve chamber into the diving bell, his feet resting against the 25 cross bars 40, grasping the handle 39. The valve 16 is then closed. Upon the closing of the valve 16 the occupant of the bell signals the divers through the window 38 and the diving bell is released by the divers carrying 30 the occupant up to the surface of the water where assistance is at hand so that he can be removed from the bell and the bell again carried downward to the divers and placed in position to remove another member 35 of the submarine crew.

If it is desired to pass a man into the submarine, such man enters the bell in the relief ship and is then lowered and secured in position by the divers who then operate 40 the hand wheel 44 to open the valve 16 and permit the man to enter the submarine, the valve being again closed by the divers.

From this description it will be seen that I have devised a very simple device where 45 by the occupants of a submarine when sunk may be readily removed and thereby overcome the loss of life usually entailed in such accidents.

What I claim as my invention is:—

50 1. The combination with the shell or wall of a submarine having an orifice therein, of a chamber depending from such orifice having an entrance opening, a closure for such opening, a valve chamber located exteriorly of the submarine wall and forming an extension of the entrance chamber, a slide valve 110

chamber, and means within the interior of the submarine for withdrawing the slide valve.

2. The combination with the shell or wall of a submarine having an orifice therein, of 65 a chamber depending from such orifice having an entrance opening, a closure for such opening, a valve chamber located exteriorly of the submarine wall and forming an extension of the entrance chamber, a slide valve extending transversely of the valve chamber to form a closure, a diving bell, means for forming a sealed connection between the lower end of the diving bell and the valve chamber, means within the interior of the submarine for withdrawing the slide valve, and means controlled from within the submarine for draining the water contained in the diving bell when secured in position. 70

3. The combination with the shell or wall 80 of a submarine having an orifice therein, of a chamber depending from such orifice having an entrance opening, a closure for such opening, a valve chamber located exteriorly of the submarine wall and forming 85 an extension of the entrance chamber, a slide valve extending transversely of the valve chamber, a lateral extension to the valve chamber into which the slide valve is withdrawn when in the open position, a threaded 90 shaft journalled in such extension meshing with a threaded orifice of the slide valve, a standard secured to the submarine floor, a water tight bearing secured to a wall of the submarine, a vertical shaft journalled in such bearing and the standard, a bevelled gear connection between the upper end of the shaft and the threaded valve shaft, a control wheel for turning the vertical shaft to carry the valve to the open or closed position, a diving 100 bell, and means for forming a detachably sealed connection between the diving bell and the upper end of the valve chamber. 95

4. The combination with the shell or wall 105 of a submarine having an orifice therein, of a chamber depending from such orifice having an entrance opening, a closure for such opening, a valve chamber located exteriorly of the submarine wall and forming an extension of the entrance chamber, a slide valve 110 extending transversely of the valve chamber to form a closure, a diving bell receiving casting secured to the upper end of the valve chamber and open at both ends, a diving bell adapted to slip freely into the receiving casting, lugs extending from the receiving casting and diving bell, and bolts for detachably connecting the opposing lugs together. 115

HENRY BROWNLEE.
